(57) **CLAIM**

The ornamental design for a wind-powered generator, as shown and described.

DESCRIPTION

FIG. 1 is a perspective view of the front, right, top aspect of an internal nacelle of a wind-powered generator according to the ornamental design;

FIG. 2 is a front view of the internal nacelle of the wind-powered generator according to the ornamental design;

FIG. 3 is a rear view of the internal nacelle of the wind-powered generator according to the ornamental design;

FIG. 4 is a left side view of the internal nacelle of the wind-powered generator according to the ornamental design;

FIG. 5 is a right side view of the internal nacelle of the wind-powered generator according to the ornamental design;

FIG. 6 is a top side view of the internal nacelle of the wind-powered generator according to the ornamental design; and,

FIG. 7 is a bottom side view of the internal nacelle of the wind-powered generator according to the ornamental design.

The broken lines are included for the purpose of showing portions of the article that form no part of the claimed design.
